FASTENER

Karl Axel Ragnar Erfass, Stockholm, Sweden

Application March 5, 1934, Serial No. 714,166
In Sweden January 26, 1934

8 Claims. (Cl. 24—245)

My present invention relates to binding clips for the suspension of garments or articles of any kind, such as socks, stockings, curtains and the like, and has particular reference to that form of binding clip which comprises a loop and a co-operating tab member so related that the material of an article to be suspended may be inserted through the loop and engaged behind the tab.

A known species of binding clips of the type just mentioned comprises a pendent loop member and a pendent strap member, said pendent strap member having a rigid terminal portion or tab e. g. consisting of a light sheet metal plate pressed on the end of said strap member and having greater length and width than those of the lower portion of said loop member. Said sheet metal plate is substantially plane surfaced on one or both sides, e. g. by being provided with a wrapper of soft material, for instance rubber, preferably on both its sides.

The principal object of my present invention is to provide a binding clip substantially as the known species just mentioned which ensures an improved gripping action of the binding clip and prevents canting of the tab on abnormal stresses or directions of stress on the article of apparel, e. g. the sock or stocking.

With this and other objects in view I provide the rigid terminal strap portion or tab with a projection of such a shape and such dimension that it does not act irritatingly or cause injury to the wearer and that the height of the apparatus in use will not be increased or but slightly increased.

In the accompanying drawing I have shown an embodiment of my improved binding clip, it being understood that this showing is merely illustrative of the invention and unrestrictive thereto. In the drawing:—

Fig. 1 is a front view of a binding clip embodying my invention.

Fig. 2 is a side view of the binding clip.

Figs. 3 and 4 are front views of the binding clip in operative position for the suspension of a garment.

Fig. 5 is a cross-section taken on the line 5—5 in Fig. 1 on an enlarged scale.

Fig. 6 shows a binding clip having a loop member of a modified form.

As described in the co-pending application above referred to the loop member 10 is formed from a single piece of wire and has a relatively wide opening 11 and a relatively narrow opening 12. The stiffening means of the lower portion or tab 13 of the strap member 14 consists of a

light sheet metal plate 15 (see Fig. 5) plane surfaced on both sides, for instance by coverings of rubber 16 or the like. The tab 13 has a greater length and width than those of the lower opening 12 of the loop member.

According to my invention I provide said tab 13 with a projection or stud 17 for the purpose to be described in the following.

In use the article of apparel or garment 18 to be suspended is brought between the strap member 14 and the loop member 10 as shown in Fig. 2, the clamping of the garment being preferably effected in such a manner as to cause the stiffened portion 13 on a pull on the garment 18 to press same against the portion of the loop member 10 limiting the opening 12.

When as shown in Fig. 3 the garment is clamped by the clip a portion of the garment extends through the loop member and overlies the face of the tab which is remote from the loop member instead of the face of the tab which is adjacent the loop member and the projection 17 is situated in said opening 12.

When a pull is exerted on the garment, e. g. in the direction of the arrow *p* in Fig. 4, the stiffened portion or tab 13 will be somewhat displaced in opposite direction, and when the pull is relatively strong the projection 17 will be pressed against the lateral edge of the opening 12. For this reason I prefer to give to the projection a shape corresponding to that of the lower portion of the loop member. The stronger the pull is, the stronger the projection will press the intermediate portion of the garment against the lateral edge of the opening 12. Consequently, the projection 17 will intensify the gripping action of the clip and will moreover prevent an unintentional canting of the tab 13 on abnormal stresses or directions of stress.

The projection 17 need not be larger than to permit its introduction into the opening 12 from the rear, that is in a direction perpendicular to the plane of the lower portion of the loop member 10 forming said opening 12. Further, the projection should not be so large as to bear simultaneously on two opposite sides of the opening 12 as thereby an unnecessary wear of the garment would arise e. g. in the same manner as in usual sock fasteners in which the garment is subjected to a strong wear due to it being clamped between a button and the clip.

The opening 12 may have any desired shape. In the example shown it is substantially rectangular and somewhat constricted by contractions 19 at its transition into the wider opening 11. In

such case I prefer to give to the projection a corresponding rectangular shape with an upper somewhat rounded edge 20 fitted to the shape of the contractions 19. However, the opening 12 and the projection 17 may e. g. have substantially circular or oval shape. Preferably the width a of the projection 17 (see Fig. 1) is approximately equal to the distance b between the contractions 19 so as to prevent the projection from being unintentionally pushed upwards through the constricted portion of the clip, when a garment is clamped in place. On the contrary, the projection together with the garment may be moved through the clip from the front or from the rear and the projection may on use be directed either outwardly or inwardly the action being the same.

As seen in Fig. 5 the height h of the projection is preferably equal to or only slightly greater than the diameter c of the wire 10 plus the double thickness d of the garment for which the fastener is mainly intended. Any additional height of the projection beyond this measure has no importance in practice but only causes an unnecessary increase of the thickness of the fastener when in use. If the height of the projection is selected in the manner described, said projection will not increase the height of the fastener in use, but the apparatus will still have as small height as possible and be devoid of projecting parts which would cause irritations in various manners.

It may be observed, however, that I may make the projection higher than described above without departing from its intended function and I may also form its top portion as a projecting cap or flange.

Fig. 6 shows a binding clip having a loop member 10 of a somewhat modified form. While in the embodiment shown in Fig. 1 the upper opening 11 is wider than the breadth of the tab 13 the corresponding upper opening 21 of the loop member shown in Fig. 6 is narrower than the tab 13. Therefore, in order to move the tab and the garment through the clip, the tab must be pushed through the opening edgewise. This may be advantageous in some cases, especially if owing to a very strong pulling or pushing action the projection 17 should force its way through the constriction b to the upper opening 21.

In order to effect a good bearing of the projection 17 on the wire limiting the opening 12, when said projection is displaced laterally under the action of a pull on the garment (see Fig. 4), I may give to the projection such a shape (see especially Fig. 5) that in cross-section it has a limiting edge bent somewhat inwardly and of a radius r greater than half the diameter c of the wire from which the clip is formed.

As material for the projection I use, preferably, rubber or any other elastic material, but I may also use any unelastic material for this purpose.

I do not necessarily limit myself to details of construction shown and described herein, since any modifications and changes can be made without departure from the scope of the invention as defined in the following claims.

What I claim is:—

1. A binding clip for the suspension of garments, comprising a pendent loop member and a pendent strap member connected to said loop member and having a rigid terminal portion consisting of a light sheet metal plate pressed on the lower end of said strap member and having a wrap of soft material so as to be substan-

tially plane surfaced on both sides, the clip in use having a garment portion inserted through said loop member and overlying the face of said terminal portion which is remote from said loop member, said rigid terminal strap portion having a projection of a size, when said portion is in operative position in relation to the lower portion of said loop member for suspension of the garment, to extend freely into said lower portion for the purpose set forth. 10

2. A binding clip for the suspension of garments, comprising a pendent loop member and a pendent strap member connected to said loop member and having a rigid terminal portion consisting of a light sheet metal plate pressed 15 on the lower end of said strap member and being covered on both sides by a thin rubber plate so as to be substantially plane surfaced on both sides, the clip in use having a garment portion inserted through said loop member and overlying 20 the face of said terminal portion which is remote from said loop member, said rigid terminal strap portion having a projection of a size, when said portion is in operative position in relation to the lower portion of said loop member for suspension 25 of the garment, to extend freely into said lower portion for the purpose set forth.

3. A binding clip for the suspension of garments, comprising a pendent loop member, a pendent strap member connected in overlying relation to said loop member, and a tab at the end of said strap member, said tab consisting of a light sheet metal plate having greater length and width than those of the lower portion of said loop member and being pressed on the end of 35 said strap member and covered on both sides by a thin non-metallic material, the clip in use having a garment portion inserted through said loop member and overlying the face of said tab which is remote from said loop member, 40 said tab having a projection of a size, when the tab is in operative position in relation to the lower portion of said loop member for suspension of the garment, to extend freely into said lower portion for the purpose set forth. 45

4. A binding clip for the suspension of garments, comprising a pendent loop member and a pendent strap member connected to said loop member and having a rigid terminal portion having greater length and width than those 50 of the lower portion of said loop member and being substantially plane surfaced on both sides, said rigid terminal strap portion having a projection adapted, when said portion is in operative position in relation to the lower portion 55 of said loop member for suspension of the garment, to extend freely into said portion and being smaller than said lower portion so as to enable its insertion into said portion in a direction perpendicular to the plane of said lower 60 portion.

5. A binding clip for the suspension of a garment, comprising a pendent loop member formed from a single piece of wire and a pendent strap member connected to said loop member and having a rigid terminal portion having greater length and width than those of the lower portion of the loop member and being substantially plane surfaced on both sides, said rigid terminal strap portion having a projection of a size, when 70 said portion is in operative position in relation to the lower portion of said loop member for suspension of the garment, to extend freely into said lower portion and having a height approximately equal to the diameter of said wire plus 75

the double thickness of the garment to be suspended.

6. A binding clip for the suspension of garments, comprising a pendent loop member and a pendent strap member connected to said loop member and having a rigid terminal portion having greater length and width than those of the lower portion of the loop member and being substantially plane surfaced on both sides, said rigid terminal strap portion having a projection adapted, when said portion is in operative position in relation to the lower portion of said loop member for suspension of the garment, to extend freely into said lower portion and having a width less than the inner width of the lower portion so as to bear on the inner edge thereof only when a pull is exerted on the suspended garment.

7. A binding clip for the suspension of garments, comprising a pendent loop member having a constriction dividing same into an upper and a lower portion, and a pendent strap member connected to said loop member and having a rigid terminal portion having greater length and width than those of the lower portion of the

loop member and being substantially plane surfaced on both sides, said rigid terminal strap portion having a projection adapted, when said portion is in operative position in relation to the lower portion of said loop member for suspension of the garment, to extend freely into said lower portion and having a width approximately equal to the distance between the sides of the loop at the constriction.

8. A binding clip for the suspension of garments, comprising a pendent loop member and a pendent strap member connected to said loop member and having a rigid terminal portion having greater length and width than those of the lower portion of the loop member and being substantially plane surfaced on both sides, said rigid terminal strap portion having a projection of a width less than the inner width of the lower portion of the loop member so as to extend freely into said lower portion when the terminal strap portion is in operative position in relation thereto for suspension of the garment.
